OIL WELL FORMATION TESTER

Filed April 23, 1948

FIG. 2

Ben W. Sewell
Robert H. Blood Inventors

FIG. 1

By W. O. Feilman attorney

Method and apparatus for sealing off a portion of an oil well, and apparatus for extracting samples of well fluids, comprising an elastic packer having a permeable section, and a chamber extending within the packer, the chamber being connected to the bore hole, and the upper portion of the chamber being connected to a telescopingly movable rod, the lower portion of the chamber being connected to a spearhead, the upper portion of the rod being connected to the spearhead, and the lower portion of the rod being connected to the packer, the upper portion of the rod being telescopingly movable relative to the lower portion of the rod, and the upper portion of the rod being movable relative to the packer.

OIL WELL FORMATION TESTER

Robert H. Blood and Ben William Sewell, Tulsa,
Okla., assignors to Standard Oil Development
Company, a corporation of Delaware

Application April 23, 1948, Serial No. 22,878

4 Claims. (Cl. 166—1)

1.

The present invention relates to a novel formation tester to be used in extracting samples of well fluids encountered in oil well drilling operations.

During oil drilling operations, the bore hole is generally filled with a fluid such as "drilling mud." The purpose of this mud is in large part to maintain a sufficiently high hydraulic pressure on the formations through which the hole is drilled so that natural fluids contained in the formations will not be uncontrollably released. If drilling mud or an equivalent fluid were not employed, gases or liquids under considerable pressure might be released by the drilling operations to be blown to the surface of the earth; in many cases to be blown to the surface of the earth under sufficient pressure to damage the drilling apparatus employed. The presence of drilling mud in the well hole, therefore, complicates the testing of fluids encountered during drilling. In the first place, the hydraulic pressure of the drilling mud substantially prevents fluids from leaving the strata being drilled and in the second place, any fluids ejected from the strata would be mixed with the drilling mud. Consequently, it is necessary to employ special testing procedures to suitably extract samples of fluids from formations being drilled. Conventionally this has been done by swabbing the oil well, that is, by reducing the hydrostatic pressure of the drilling mud sufficiently to allow fluids to be released from formations and to be drawn upwardly in the well hole. This procedure has not been particularly satisfactory however, so that at the present time attempts are being made to develop more suitable well testing procedures.

Methods are now being developed for sealing off a particular portion of the oil well permitting the reduction of pressure on this portion of the well so that the drilling fluid may be extracted from the particular portion without decreasing the hydraulic pressure on the remaining portions of the well. The apparatus developed for this purpose is generally called "formation testing apparatus." A particularly useful form of formation testing apparatus which has been developed is that involving an elastic packer. This type of packer is adapted to be supported in a bore hole at a desired point and to be expanded to seal off the hole at that point. By incorporating means in or adjacent to the wall of the packer for extracting a sample from the strata, a fluid sample may be extracted from the earth at the particular point and may be drawn to the sur-

face of the earth. The present invention is directed to an improved form of elastic packer, formation-testing-apparatus. The particular object of this invention is to enable formation testing to be made with a minimum of effort and a maximum of ease. At the same time the apparatus of this invention is of simple construction.

The nature and objects of this invention may be fully understood from the following description 10 in connection with the accompanying drawings in which Fig. 1 diagrammatically illustrates an embodiment of the invention suspended in an oil well in the inflated or sealing position, while Fig. 2 represents the same embodiment of the 15 invention suspended in the well in a deflated position.

Referring to the drawings it will be understood 20 that the apparatus illustrated is positioned in an oil well 1 at any desired depth. The apparatus 20 is suitably supported in the oil well by attachment to a drill stem identified by the numeral 2. The drill stem 2 is of conventional construction and consists essentially of a string of pipe suitably connected by threads and couplings. It is 25 only necessary that the drill stem terminate in a suitable threading to accommodate the novel apparatus illustrated in the drawing. It is to be understood that the formation tester of this invention comprises all parts of the drawing below the drill stem 2. Suitably connected to the drill 30 stem 2, by means of the threads illustrated or by equivalent means, is a cylindrical casing or housing 6. The lower part of the casing 6 is used as the termination and support of the elastic packer suspended below the housing. This packer is 35 identified by the numeral 4 and is shown to be composed of rubber or an equivalent elastic material. Around one circumference of the elastic packer, preferably positioned about midway of the ends of the packer, is a permeable section 10. This permeable section of the packer is an integral part of it and may conveniently be composed of permeable rubber such as is now commercially available. Contained within the elastic 40 packer are a multitude of pellets 18. These may be of rock, glass, metal or any other desired inert packing material and serve to fully, but porously, pack the elastic packer. The lower part of the elastic packer terminates in and is supported by 45 an inner rod 5 which extends upwardly into the casing 6. The upper portion of this rod is preferably terminated in a spearhead 3. A chamber 7 extends within the rod 5 from a point opening 50 into the bore hole beneath the lower termination 55 of the packer to connect with the telescoping

passage 30, providing a continuous passageway upwardly to the by-pass port 12 which opens to the fluid filled bore hole. Another passageway extends from ports or chambers 15 in the upper part of rod 5, downwardly through the rod 5, to terminate in the perforated openings 16 which are positioned within the elastic packer. This chamber connecting the perforations 16 in rod 5 and the upper port 15 in the rod 5 is identified by the numeral 13. It will be noted that a check valve 14 is also positioned in the passage 13 to permit the flow of fluids upwardly through this chamber, but to prevent the flow of fluid downwardly. At the upper part of the rod 5 adjacent to the spearhead 41 are latching dogs 8. These are adapted to swing outwardly or inwardly to engage or disengage the projections 9 provided on the inner part of the housing 6. The latching dogs are urged outwardly by springs not illustrated in the drawing. The general structure of the apparatus of this invention having now been described and identified, the operation of this apparatus may be understood.

A suitable well hole 1 is drilled in the earth by conventional drilling operations. Generally during these drilling operations, by means of well logs or other means known to the art, some indications as to possible oil-bearing strata in the earth are obtained. Thus, by suitable well-logging means it may be established that a porous stratum 11 exists at some point of the oil well. In order to test the fluid which may be present in the porous stratum 11 the apparatus of this invention is then employed. The drill stem is removed from the well and the conventional drilling tools removed from the end of the drill stem. The apparatus illustrated in the drawing is then connected to the end of the drill stem as shown permitting the entire apparatus to be lowered into the well. Prior to this operation, the latching dogs are manually depressed so that rod 5 sliding on guides 20, is allowed to drop downwardly with respect to casing 6, holding the elastic packer in the deflated or extended position shown in Figure 2, while the apparatus is lowered. The apparatus is lowered until the porous section of the elastic packer is adjacent to the porous stratum to be tested. Thus, as shown in Fig. 1 the elastic packer is lowered sufficiently in the well so that the porous section 10 of the elastic packer is adjacent to the porous stratum 11 of the earth. As stated, while the apparatus is being lowered into the well the elastic packer is in the deflated position as shown in Figure 2. In the deflated or extended position, the rod 5 within the elastic packer and the components associated with rod 5 exert sufficient weight on the packer to hold it in the elongated position as illustrated. In this position the latching dogs 8 on the upper part of rod 5 are below the shoulders 9 provided in the chamber 6. When the apparatus has been suitably positioned in the well, a wire line equipped with a suitable latch on it is dropped down the drill string to engage the spearhead 3 of the apparatus. By exerting a pull on the wire line at the surface of the earth, the rod 5 is pulled upwardly with respect to the chamber 6. The upward movement of rod 5 will bring the latching dogs upwardly to the portion of chamber 6 provided with the latches or shoulders 9. At the same time the upward movement of rod 5 will shorten the elastic packer, causing it to extend laterally to completely fill and seal the well. It will be noted that the elastic packer is filled with a

multitude of pellets 18 which give the elastic packer sufficient body so that the pulling upwardly of rod 5 will cause the packer to press against the walls of the drill hole so as to completely seal the hole. When sufficient force has been exerted on the wire line connected to spearhead 3 so that operators at the surface know that the flexible bag has been fully sealed against the wall of the hole, the wire line may be disengaged by suitable and conventional means. The latching dogs 8, engaging the shoulders 9, will hold the apparatus in the inflated position shown in Figure 1. The apparatus is now in suitable condition for withdrawing a fluid sample from the stratum 11.

It is apparent that in the preceding description the terms "inflated" and "deflated" position of the packer have been loosely used to describe the sealing and non-sealing positions. Strictly no inflation or deflation occurs since the only change in the condition of the packer is a change of shape.

With the apparatus in the position and condition shown in Figure 1, in order to withdraw fluid from the stratum 11 it is only necessary that the hydrostatic head of drilling mud existing in the drill stem 2 be reduced sufficiently. This may be accomplished by any desired means such as employing a piston pump or other pump to reduce the hydrostatic pressure of the drilling mud in drill stem 2. Thus by pumping out at least a portion of the drilling mud in the stem the pressure existing on the check valve 14 is decreased. When the pressure has suitably been diminished so that the pressure in stratum 11 is greater than the hydrostatic pressure existing at the bottom of the drill stem 2, check valve 14 will open and fluid from stratum 11 will begin to permeate the porous section 10 of the elastic packer. This fluid will gradually pass through the pellets contained in the elastic packer and will pass through the perforations 16 of rod 5 to enter the chamber 13. The check valve 14 will permit the flow of the fluid upwardly through chamber 13 and outwardly through the ports 15 to the inner portion of chamber 6 which is associated with the inside of drill stem 2. Consequently by suitably decreasing the hydrostatic pressure in the drill string fluid will be drawn through the path indicated, upwardly through the drill stem, to the surface of the earth for suitable examination. It may be noted that the function of passageway 7 and 30 during these operations is to maintain an equal pressure above and below the packer so that no vertical component of force will be exerted on the packer.

After a suitable fluid sample has been obtained as described, it is necessary to deflate the elastic packer in order to permit removal from the well or to permit testing at another portion of the well. Deflation of the packer is accomplished by dropping a suitable unlatching sleeve through the drill stem to fall over the spearhead 3 of the apparatus and over the latching dogs 8. This unlatching sleeve is diagrammatically indicated in the drawing and is identified by the numeral 45. It will be noted that the unlatching sleeve consists essentially of a cylindrical member which will suitably fit over the spearhead having downwardly extending ends which will engage the latching dogs 8. The ends of the unlatching sleeve are indicated by the numeral 42 and are preferably beveled as to suitably depress the latching dogs 8 so as to permit disengagement 75 of these latching dogs from the shoulders 9.

While the upper part of the unlatching sleeve is not shown, the design of this portion of the sleeve is not critical. It is preferred, however, that the upper portion of the sleeve be equipped with a spearhead to permit withdrawal of the sleeve as desired. On withdrawing the sleeve a further fluid sampling operation may be conducted at a different portion of the well. It will be noted that when the unlatching sleeve is dropped down through the drill string the latching dogs will be depressed by the ends 42 of the unlatching sleeve. Depressing the latching dogs will permit the weight of the rod 5 and the associated parts to extend the elastic packer downwardly to the deflated position as indicated in Fig. 2.

As described, the novel formation testing apparatus of this invention consists of a packed elastic sealing means which may be suitably sealed against the wall of the drill hole by shortening its inner support. The sealing of the packer against the wall permits the hydrostatic pressure on the inner part of the packer to be reduced and at the same time brings a porous portion of the packer in contact with strata adjacent the bore hole. By this means it is possible to readily and simply remove fluid from the strata, bringing the fluid to the surface through the drill stem on which the apparatus is supported. The novelty of this apparatus will be made clear from the appended claims.

1. Improved formation tester apparatus for well bores comprising a first hollow elongated supporting member, a second elongated supporting member at least a portion of which is slidably fitted within said first supporting member, an elastic packer fixed at one end to said first supporting member and at its other end to said second supporting member whereby lengthwise movement of said second supporting member relative to said first supporting member causes lateral changes in the shape of said packer, said packer being constructed of impermeable flexible material and provided with a porous wall portion intermediate its ends, said packer and said supporting members defining between them an annular space, pelleted packing material maintained within said annular space, and conduit

means connecting said annular space with the interior of said first supporting member.

2. Apparatus according to claim 1 including latching means pivotally attached to the portion of said second supporting member which is slidably fitted within said first supporting member and latching means attached within said first supporting member adapted to engage said first named latching means and thereby control the slideable movement of said second supporting member relative to said first supporting member.

3. Apparatus according to claim 1 including a passageway extending through said elastic packer and provided with exterior openings above and below said packer.

4. Improved formation tester apparatus for well bores comprising a pair of tubular supporting members adapted for longitudinal movement with respect to each other, at least one of said members having a chamber adapted to receive fluid, an elastic packer attached at one end to one of the said supporting members and at the other end to the other supporting member in a manner adapted to effect lateral changes in said packer upon said movement of said supporting members with respect to each other and defining with said supporting members an enclosed space, said packer being constructed of impermeable flexible material and provided with a porous wall portion intermediate its ends, pelleted packing material within said enclosed space, and conduit means connecting said enclosed space with said chamber in said supporting member.
